H. H. Stevens
His ATTORNEY

UNITED STATES PATENT OFFICE.

CHARLES H. STEBBINS, OF ROCHESTER, NEW YORK.

RECEPTACLE.

1,174,099.

Specification of Letters Patent. Patented Mar. 7, 1916.

Application filed March 25, 1915. Serial No. 16,908.

To all whom it may concern:

Be it known that I, CHARLES H. STEBBINS, of Rochester, in the county of Monroe and State of New York, have invented a new and useful Receptacle, fully set forth in the following specification and shown in the accompanying drawings.

The present invention relates to receptacles and more particularly to that type having a slip cover with means arranged to operate between the body and the cover for the purpose of readily removing the cover from the body, an object of this invention being to provide a construction which has its movements on the receptacle limited so that it will at all times be in a position for removing the cover when the cover is fitted to the box body or will be in a position permitting the cover to be fitted to the body without any readjustment of the operating or removing device after the removing operation.

To these and other ends, the invention consists in certain parts and combinations of parts all of which will be hereinafter described, the novel features being pointed out in the appended claim.

In the drawings: Figure 1 is a view in side elevation of the receptacle showing the cover in position upon the body; Fig. 2 is a view similar to Fig. 1 showing the cover removing device shifted to lift one side of the cover on the body; Fig. 3 is a plan view of the receptacle; Fig. 4 is a section on the line *a—a*, Fig. 3, with the cover fitted to the body; and Fig. 5 is a section on the same line showing the cover partially removed.

Referring more particularly to the drawings, 1 indicates the box or receptacle body which is of the ordinary form employed for containing paste or blacking, the box in this instance having below its upper edge, a surrounding bead 2, that portion 3 of the body above the bead being adapted to fit within the cover 4, which, in this instance, also has a surrounding bead 5 above its lower edge. When the cover is fitted to the box body, the two beads 2 and 5 lie in spaced relation, the lower edge of the cover being in abutment with the bead 2.

The cover removing device is in the form of a lever 6 pivoted between its ends at 7

preferably to the side wall of the body below the bead 2, said lever being curved transversely in order to conform to the curvature 55 of the box body and having at one end, an outwardly turned portion 8 which serves as a finger piece for manipulating the lever. At the opposite end of the lever, an upward laterally extending arm is provided which 60 is bent between its ends to provide a recess 9 that receives the bead 2 in order that the extreme end 10 of the arm may lie above the bead 2 and below the bead 5 when the cover is fitted to the body 1. The opposite 65 ends of this recess serve to limit the movement of the lever on the box body 1 and, in this way, when the lever is moved to remove the cover, it cannot pass beyond a certain point and consequently the end 10 will 70 be engaged by the cover bead 5, when the cover is fitted to the body, thus carrying the opening lever back to the position shown in Fig. 1 with the fitting of the cover to the box body. When the cover is fitted to the 75 body, the position of the end 10 between the beads 5 and 2 prevents any free movement of the operating lever on the box body.

From the foregoing, it will be seen that there has been provided a receptacle with a 80 cover moving device which is held against undue movement on the receptacle and which only requires a manipulation for the purpose of removing the cover, as it is automatically moved to the normal position 85 when the cover is fitted to the body.

What I claim as my invention and desire to secure by Letters Patent, is:

In combination with a box body having a surrounding bead below the upper edge of 90 the body and a slip cover for said box body coöperating with the exterior of the latter above the bead and having a surrounding bead above the lower edge of the cover, an operating lever pivoted to one of said parts 95 and having a laterally extending arm formed with a portion to lie between the beads and having a recess to pass above the bead on the part on which the lever is mounted, the end walls of the recess coöperating with the 100 bead to limit the movement of the lever in two directions.

CHARLES H. STEBBINS.
